UNITED STATES PATENT OFFICE.

CHARLES ANDERSON, OF SOUTH BEND, INDIANA, ASSIGNOR TO THE SOUTH BEND IRON WORKS, OF SAME PLACE.

SULKY-PLOW.

SPECIFICATION forming part of Letters Patent No. 476,355, dated June 7, 1892.

Application filed March 3, 1892. Serial No. 423,630. (No model.)

To all whom it may concern:

Be it known that I, CHARLES ANDERSON, a resident of South Bend, in the county of St. Joseph and State of Indiana, have invented certain new and useful Improvements in Sulky-Plows; and I do hereby declare the following to be a full, clear, and exact description of the invention, such as will enable others skilled in the art to which it appertains to make and use the same.

My invention relates to an improvement in sulky-plows, the object being to construct a plow of this class in such manner that it may be effectually turned to the right or to the left on the road or when at work by simply guiding the horses in the direction desired.

A further object is to construct the device in such manner that the ground or carrying wheels will be shifted when the horses are driven to one side to make a turn, and so that the furrow or caster wheel will automatically, and without the necessity of being unlocked, partake of the same shifting movement as the ground or carrying wheels, and thus facilitate the turning of the plow.

A further object is to construct a sulky-plow in such manner that ample provision will be made for turning either to the right or left, and so that when the team moves directly forward all the parts will come promptly and automatically back to their normal positions, the plow carriage and bottoms being held in rigid positions, so that uniform work will result.

A further object is to so construct a sulky-plow that simplicity and strength will be united, and so that economy of labor, both to the plowman and the team, will follow.

With these objects in view the invention consists in certain novel features of construction and combinations and arrangements of parts, as hereinafter set forth, and pointed out in the claims.

In the accompanying drawings, Figure 1 is a plan view of my improved plow. Fig. 2 is a side elevation with one of the ground or carrying wheels removed. Fig. 3 is a detail view.

A A' represent the plow-beams, to which

the plows B B' are secured. A bracket C is located between the rear ends of the beams A A', and is secured thereto and to the plows B B' by means of suitable bolts a. The bracket C is provided at its rear end with a vertical perforated boss C', in which the shank b of a caster or furrow wheel D is adapted to operate, said shank being provided with a rigid arm d, for a purpose hereinafter explained. The bracket C also serves as a support for a driver's seat C².

A flanged spacing-plate E is secured to the beams A A' between their forward ends by means of suitable bolts e passing through the flanges of said plate and the beams. The forward ends of the beams A A' rest upon a saddle F, to the ends of which a saddle-plate or yoke G is secured, said saddle-plate or yoke being adapted to extend over the beams A A' and parallel with the saddle F. The spacing-plate E is provided at a point in proximity to the beam A with a perforated boss f for the passage of a bolt f', said bolt also passing through one of a series of perforations f² in the saddle and one of a series of perforations f³ in the saddle-plate or yoke, and thus the beams A A' will be pivotally connected with the saddle and saddle-plate at one side of the center thereof, the said saddle and yoke forming a swinging frame.

The saddle F is provided with forwardly-projecting arms g, in which an axle H is mounted, to one end of which a crank-arm G' is adjustably secured and carries one of the ground or carrying wheels H'. Projecting downwardly and forwardly from the end of the saddle F opposite the ground or carrying wheel H' is a skein h, on which a thimble h' is loosely mounted. The lower end of the thimble h' is made with a perforated boss for the accommodation of a skein, on which the ground or carrying wheel H² is mounted. The free end of the thimble h' is recessed to permit the loose attachment thereto of a link h², and the lower end of the said thimble is provided with ears h³, between which the end of a link h⁴ is pivotally connected. The upper ends of the links h² h⁴ are pivotally connected to the ends of a lever h⁵. The lever h⁵ is pivoted at a point between its ends to a

projection on a lever I, which lever is loosely mounted on one end of the axle H and carries a latch-bar h^6 , adapted to engage a toothed segment h^7 , secured to the axle H, said lever 5 I also carrying latch-operating devices. By manipulating the operating-lever I the furrow-wheel H^2 can be properly adjusted, as described in my former patent. An operating-lever I' is secured to the axle H in proximity to the free end thereof and carries a spring-actuated latch-bar i, adapted to engage a segment i' , secured to the saddle F. By manipulating this lever I' the plows will be raised or lowered.

15 The spacing-plate E is made with a downwardly and forwardly projecting portion j , from one side of which an arm j^3 projects forwardly and laterally. Pivotedly connected to the arm or portion j of the plate E, at one 20 side thereof, are U-shaped evener guide-plates K, the other ends of said guide-plates being also connected with the arm j at the opposite side thereof by means of a bolt j' , which passes through the ends of said guide-plates 25 and through an elongated slot j^2 in the arm j . A bracket l is located between the guide-plates K and is pivotally connected thereto (at the furrow side thereof) by means of a bolt l^7 . The long draft-bar L of a draft- 30 evener is secured in the bracket l and is connected with a lug l^5 , projecting from the saddle F forwardly of the axle, by means of an adjustable two-part bar L^2 . The bar L^2 comprises two sections m m' , the section m being 35 loosely connected with the lug l^5 and having its other end screw-threaded for the reception of a nut l^6 , said screw-threaded end being adapted to pass through a perforated ear m^2 , projecting from the section m' . The 40 outer end of the section m' is connected with the draft-bar L by means of a bolt l^3 , which passes through an elongated slot l^4 in said section m' . From this construction it will be seen that the movements of the horses attached to the draft-bar L will be compensated 45 for without effecting any change in the positions of the wheels relatively to the plow-beams and plows. Pivotedly connected to the arm j^3 of the arm j of the plate E is the curved 50 short draft-bar L' of the evener, said short draft-bar passing loosely between the parts of the bracket l, and is retained from escape from said bracket by means of a pin n in the end thereof. A lever M is pivoted at a point between its ends in the forward ends of the 55 guide-plates K and has journaled in its ends anti-friction rollers M', which run on the edge of the short draft-bar L' and the bracket which supports the long draft-bar L, or on the edge 60 of the draft-bar L itself. The free ends of the draft-bars L L' of the evener will be provided with suitable elevises I^3 .

Connected at one end to the bolt l^7 and at the other end to the saddle F is a two-part adjustable bar O. This bar O comprises sections o o' , the section o being pivotally connected at one end to the saddle F and at the

other end provided with screw-threads and adapted to pass through a screw-threaded perforation in an ear o^2 , projecting from the section o' of said lever. The outer end of the section o' is made with an elongated slot o^3 for the reception of the headed end of the bolt l' . A curved bar or rod P is loosely connected at one end to a bolt p , inserted in one of a series of perforations p' in the saddle-plate or yoke G, and at the other end said curved bar or rod is loosely connected with the arm d on the stem of the caster-wheel D.

The object of the construction and arrangement of the adjustable bar O is to set the wheels in uniform position to do their work, giving them more or less gather, as desired. The object of the slot o^3 in the section o' of the bar O is to permit the turn of the wheels 85 to any desired angle, the length and scope of the turn being decided by the slot. By providing the slot in the bar L' ample room will be provided for the unequal movement of the horses and for the purpose, too, of aiding in 90 the turning of the wheels when a tongue is not used.

If desired, a tongue may be secured between arms q, projecting upwardly from the saddle-plate G. An eye r may be secured to 95 the plate E for the reception of the shank of a colter.

With the machine constructed and arranged as above described efficient means will be provided for turning the plow either when 100 at work or on the road, and this is effectually accomplished automatically, so that a turn may be made to the right or left without difficulty by simply guiding the horses in the direction desired. When the horses are guided 105 to one or the other direction, the carrying-wheels will be properly shifted or turned relatively to the plow-beams and plows and the caster-wheel will be automatically shifted (without the necessity of unlocking) to partake of the same movement. When plowing, the caster-wheel will be held strictly in place and prevented from climbing out of the furrow. By means of my improvements, also, 110 all side draft will be obviated, and should a tongue be used the horses' necks will not suffer in the least.

The plow can be used with or without a tongue, as preferred, or as circumstances may dictate. By virtue of the connections hereinbefore explained with the draft features of the plow the caster-wheels respond to and adapts itself to any turn that may be made, insuring uniform plowing and perfect work.

Having fully described my invention, what I 125 claim as new, and desire to secure by Letters Patent, is—

1. In a sulky-plow, the combination, with the beams and a swinging axle-frame carrying wheels, of a spacing-plate secured between 130 said beams, draft devices connected to said spacing-plate, a pivoted caster-wheel, and a connection between the axle-frame and said caster, whereby the two will be turned simul-

taneously when the team is turned, substantially as set forth.

2. In a sulky-plow, the combination, with the beams and a swinging axle-frame, of draft devices, a pivoted caster-wheel, a connection between said caster-wheel and swinging axle-frame, and an adjustable bar pivotally connected at one end to the axle-frame and at the other end with the guide-plates of the draft devices, substantially as set forth.

3. In a sulky-plow, the combination, with the beams and a swinging axle-frame, of draft devices, a pivoted caster-wheel, a connection between said caster-wheel and swinging frame, and an adjustable bar pivotally connected at one end to the swinging frame, the other end of said bar being made with an elongated slot and connected with the guide-plates of the draft devices, substantially as set forth.

4. In a sulky-plow, the combination, with a swinging frame carrying wheels and draft devices having guide-plates, of a bar pivotally connected at one end to the swinging frame and provided at its other end with an elongated slot and connected with the guide-plates of the draft devices, substantially as set forth.

5. In a sulky-plow, the combination, with a swinging frame carrying wheels and draft devices comprising a long and a short bar, of a bar connected at one end to the swinging frame and at the other end to the long bar of the draft devices, substantially as set forth.

6. In a sulky-plow, the combination, with a swinging frame, and wheels carried thereby, and draft devices comprising a long and a short bar, of a pivoted caster-wheel, a connection between the caster-wheel and swinging frame, and a bar connected at one end with the swinging frame and at the other end to the long arm of the draft devices, substantially as set forth.

7. In a sulky-plow, the combination, with a swinging frame, wheels carried thereby, and draft devices comprising a long and a short

draft-bar, of an adjustable bar connected at one end to the long bar of the draft devices and at the other end to the swinging frame, substantially as set forth.

8. In a sulky-plow, the combination, with a swinging frame carrying wheels and draft devices comprising a long and a short draft-bar, of a bar connected at one end with the swinging frame and provided at its other end with an elongated slot and connected with the long bar of the draft devices, substantially as set forth.

9. In a sulky-plow, the combination, with a swinging frame, beams, and a spacing-plate rigidly secured to said beams, of guide-plates secured to the spacing-plate, a short draft-bar also connected to said spacing-plate, a larger draft-bar carried by the guide-plates, and a lever pivoted to the guide-plates and bearing against the front edges of both draft-bars.

10. In a sulky-plow, the combination, with plow-beams and a spacing-plate secured between them, of U-shaped guide-plates pivotally connected at one end to said spacing-plate and having a sliding connection at their other ends with said plate, and draft devices connected to said guide-plates, substantially as set forth.

11. In a sulky-plow, the combination, with plow-beams and a spacing-plate, of guide-plates connected thereto, a bracket pivotally connected between said guide-plates, a long draft-bar secured to said bracket, a short draft-bar pivotally connected to said spacing-plate and passing through said bracket, and a lever pivoted between its ends to the guide-plates and bearing against the draft-bars, substantially as set forth.

In testimony whereof I have signed this specification in the presence of two subscribing witnesses.

CHARLES ANDERSON.
